UNITED STATES PATENT OFFICE

2,298,290

VISIBLE RECORD SYSTEM

Marchand B. Hall, Chicago, Ill., assignor to Acme
Visible Records, Inc., Chicago, Ill., a corpora-
tion of Delaware

Application January 16, 1941, Serial No. 374,631

19 Claims. (Cl. 129—16)

This invention relates to improvements in visible record systems, and particularly to the type wherein means are provided whereby one or more record cards hingedly or swingably mounted upon hangers, disposed in spaced overlapping relationship upon a suitable support or tray, may be displaced or laterally offset either to the right or left with respect to the central or normal position of the remaining cards upon the tray or supports, and may be positively maintained in central or in offset position in either direction.

Lateral displacement and positioning means in combination with visible record systems as herein contemplated find use as either temporary, permanent or periodically variable identification, classification, follow up, or like signal aids, as for example, in the classification of postings, credit ratings, payment or collection follow-ups, purchase, order, or service reminders and the like. A device adapted for like use is set forth in United States Patent No. 1,993,510 to Edward C. Gast, Jr., dated March 5, 1935.

The laterally offsetting and positioning means of the present invention is adapted for use in combination with conventional visible index frames or supports utilized as trays or drawers of record cabinets, leaves of record books, units of the usual swingably mounted record or index stands and the like, without modification thereof. Likewise, the card hanger mounting means, as hereinafter more fully described, are interchangeable with conventional card hangers not provided with lateral card displacement means, with other card hangers provided with lateral displacement means such as set forth, for example, in my Patent No. 2,246,584 dated June 24, 1941, and if desired, a single frame or tray may contain several classes of card hangers.

As a feature of the present invention, the card hangers are provided with individual mounting supports, the supports being adapted to be positioned on the tray or holder and retained by the conventional flanges thereof against movement laterally of the frame, so that no friction impediment is set up between the lateral displacement means of adjacent supported cards, and as a result, tendencies of the hangers to buckle, shift, collapse or to become displaced in the holder are eliminated with the result that freedom of lateral movement and positioning of the cards without interference from or contact with adjacent hangers is maintained at all times. Various other objects and advantages of my invention relating to the utility thereof, its economies, arrangement of parts and modifications thereof, will be ap-

parent from a consideration of the following specification and drawings, wherein:

Fig. 1 is a front elevational view illustrating a fragmentary portion of a record or index unit embodying one form of my improved offset hanger mounting device.

Fig. 2 is an enlarged sectional view taken on the line 2—2 of Fig. 1.

Fig. 3 is an enlarged front face elevational view of a hanger mount and operatively associated hanger as embodied in Fig. 1, the hanger being in normal or central position.

Fig. 4 is a view similar to Fig. 3 showing the hanger in right offset position.

Fig. 5 is a view similar to Fig. 3 showing the hanger in left offset position.

Fig. 6 is a perspective view of a wire card hanger, of the type shown in association with the mounting means in the previous figures.

Fig. 7 is a perspective view of a wire card hanger of the type embodied in the following figures:

Fig. 8 is a front elevational view illustrating a fragmentary portion of a record or index unit embodying a modified form of my improved offset hanger mounting device.

Fig. 9 is a rear face elevational view of the hanger mount and operatively associated hanger, embodied in Fig. 8.

Fig. 10 is a section on the line 10—10 of Fig. 8.

Fig. 11 is a section on the line 11—11 of Fig. 8.

Fig. 12 is a front elevational view illustrating a fragmentary portion of a record or index unit embodying another modification of my improved hanger mounting device.

Fig. 13 is a rear face elevational view of the hanger mount and operatively associated hanger, embodied in Fig. 12.

Fig. 14 is a section on the line 14—14 of Fig. 12.

40 In general my improved offset hanger mounting means comprises two members, one of which is substantially in the form of a conventional card hanger as well known in the art comprising a flexible wire formed with return end bent portions, the return bent portions being adapted to

45 swingably support a record card by means of eyelets or hinges, the second member being in the form of a relatively flat flexible metal strip. The strip which comprises the mounting member is adapted to be positioned on a conventional tray or holder by means of the flanges thereof, where-
50 by it is retained against movement laterally of the frame. The hanger is engaged to the mount-
ing strip in a manner whereby it may be offset or be shifted longitudinally thereof, or laterally

with respect to the frame the two portions being additionally provided with cooperative means, or the parts having portions, which cooperate for the purpose of yieldably positioning the hanger in a manner whereby it may be retained either in the normally central position or in an offset position in either direction from said central position, all without shifting or movement of the hanger mount in its position on the frame.

Referring to the drawings, and particularly Figs. 1 to 6, the conventional card holder frame 10 provided with channels 11 receives the mounting means 12 by its end portions in a manner similar to that in which ordinary card-hangers are engaged. The hanger mount 12 comprises a generally flat elongated strip of metal and is provided adjacent to and slightly inward of its ends with the U bent portions 13. This results in the base of the U bent portions being elevated in a plane parallel to and spaced apart from the main body of the mount 12. The base of each of these U portions 13 is provided with an indentation to result in the lugs 14 which extend inwardly or rearwardly, these lugs being of generally elongated form extending longitudinally of the strip 12.

To each of these strips 12 there is engaged a wire hanger 15 by means of its return bent end portions 16 in a manner whereby the body of the hanger generally lies on the front face of the mounting strip 12 with the return bent end portions looped through the U bends and around the offset legs 17. These offset legs 17 are of reduced width so as to permit free sliding action of the hanger 15 at its doubled end portions with respect to the strip 12, the overall width of the strip 12 being substantially equal to the overall width of the hanger 15 and its said end portions. As will be noted, the overall length of the hanger 15 is less than that of the mounting strip 12, and is of a length sufficient to embrace the two spaced apart lugs 14. It will also be noted that the height of the offsetting legs 17 are such as to permit free sliding movement and clearance of the return bent doubled end portions of the hanger, but the inward projection of the lugs 14 is such as to impede this free sliding movement and to normally maintain the hanger and its mounting strip in the central position indicated in Figs. 2 and 3.

The terminal ends of the hanger 12 are slightly offset as at 18 for the reception of the eyelets 19 of an index card 20, it being understood, however, that although the drawings disclose the record or index cards to be provided with eyelets whereby they may be swingably mounted, the index cards may be provided with the conventional hinges well known in the art in lieu of eyelets, and engaged to the hangers by slightly modified offset terminal ends, also conventional in the art.

By grasping an engaged card 20 and shifting it laterally either to the right or left, one of the return bent end portions 16 of the hanger will be caused to flex and slide over its corresponding positioning lug 14 so as to bring one of the return bent end portions in endwise abutment with a lug 14 as shown in Fig. 4 or Fig. 5, to be maintained in such position until again manually displaced.

Figs. 7 to 11 disclose a modified offset hanger mounting means comprising the hanger mount 21 supporting in operative association therewith the hanger 22. This mount 21, similar to mount 12 previously described, is formed of a generally

flat elongated strip of metal and is provided adjacent to and slightly inward of its ends with the U bent portions 23. This results in the base of the U bent portions 23 being elevated in a plane parallel to and spaced apart from the main body of the mount 21. To the mount 21 is engaged the wire hanger 22 by means of its return bent end portions 24 in a manner whereby the body of the hanger generally lies on the front face of the mount 21 with the return bent end portions looped through the U bends and around the offset legs 25. These offset legs 25 are of reduced width so as to permit free sliding action of the hanger 22 at its double end portions with respect to the mounting strip 21, and if desired, the entire U bent portion may be of like reduced width, since I do not provide the base of the U bend with engagement lugs as in my previously described form. The overall width of the mount strip 21 is, however, substantially equal to the width of the hanger at its double end portions so as to maintain the hangers on their engaged mounts in properly spaced apart relationship from adjacent hangers on the frame 10. The overall length of the hanger 22 is less than that of the mounting strip and in the normal central position the length is such that the bent ends of the hanger extend to substantially the mid portion of the U bends. Likewise the height of the offsetting legs of the U bends are such as to permit free sliding movement and clearance of the double end portions of the hanger and to maintain the main stretch of the hanger in close proximity to the face of the strip 21. The terminal ends of the hanger 22 may be formed as illustrated with offset portions 26 for the reception of eyelets 27 of index card 28, it being understood as set forth in connection with the previously described form, that index cards provided with hinges may be used in a similar manner.

Intermediate of its length the mounting strip 21 is provided with a rib 29 extending transversely thereof, and the hanger 22 is provided intermediate its length with a plurality of crimps, such as the crimps 30, 31 and 32 extending upwardly at an angle to the face of the plane determined by the bent portions 24. It will be noted that although the main portion of the hanger 22 is retained in close relationship to the mounting strip 21 by means of the in-turned bent portions looped through the U bends 23, the hanger 22 may be additionally maintained on the face of the strip by means of the lug 33 struck up toward the front face at the edge of the rib 29, to aid in preventing accidental displacement and for maintaining their operative association.

It can readily be seen that cards 28 carried by hangers 22 may be displaced laterally when desired so as to position any of the crimps 30, 31 or 32 in engagement with the rib 29, the figures showing the crimp 30 engaged to the rib 29 to maintain the hanger in central or normal relationship, and by shifting the card either to the right or to the left engagement will be caused with either crimp 31 or crimp 32 respectively. In this manner the cards may be shifted to the right or left of the normal central position, the hangers and associated cards will be maintained against accidental or unintentional displacement. It will be understood, of course, that in addition to the crimps 31 and 32 additional crimps may be formed on the hangers to provide any desired number of offset positions. Further,

although the rib 29 is shown at substantially the center of the strip 21, it will be understood that the rib, and correspondingly the crimps on the hanger may be formed at any other intermediate point where they may freely cooperate.

It will also be noted that although in this form of my invention I have shown the overall length of the strip 21 to be less than the width of the frame 10 so that the ends of the strip do not extend fully beneath the flanges 11, as for example, shown in my previously described form, firm positioning against movement laterally of the frame, in the present form and likewise in the previous form, results from abutment of the outermost legs of the U bends against the in-turned marginal edges of the flanges 11.

It will also be understood that although the form of my invention shown in Figs. 8 to 11 requires the use of the hanger with crimps intermediate its length as shown in detail in Fig. 7, this same form of hanger may be used in cooperative relationship with the mount 12 described in Figs. 1 to 5, although in such relationship the crimps will be without utility. It will, however, be seen that a single form of hanger such as shown in Fig. 7 may be used if desired for the purposes of economy with either of the two foregoing forms of my invention, or with the third form of my invention subsequently described.

Figs. 12 to 14 illustrate another modification of my invention wherein the laterally offset mounting means comprises the generally flat elongated metallic strip 34 positioned on the frame or holder 10 by means of the flanges 11, the length of the strip 34 being such as to extend fully beneath the flanges 11 and to cause it to be positioned against movement laterally of the frame. Positioned on the front face of the strip 34 and slidably engaged thereto by means of a plurality of lips 35 is the hanger 22. The width of the strip 34 is substantially equal to that of the hanger 22 at its double return bent end portion 24. This strip, similar to strip 21, is provided with a rib 36 intermediate its length for cooperative engagement with the crimps 30, 31 and 32 of the hanger 22, for cooperative offsetting relationship in the manner described with respect to the hanger 22 and mount 24 of Figs. 8 to 11.

It will thus be seen that in the several forms of my invention I provide essentially a mounting strip which is adapted to be detachably mounted and positioned on a holder frame therefor against lateral movement of the frame, having a wire card hanger adapted to swingably support a record card, in slidable engagement and operative association with the strip, the mounting strip being provided with one or more surface projections adapted to cause yieldable engagement with hanger portions, the hangers being known to the art, whereby although the mounting strip remains in position against lateral movement, the hanger and associated card may be moved laterally into a predetermined and yieldably retained laterally offset position, the associated portions of the mounting means comprising a firm and rugged device and which maintains adjacent laterally movable hangers in spaced apart relationship with each other when positioned on a holder frame, and permits them to operate freely and positively at all times.

I claim as my invention:

1. In a visible card system, the combination with a frame having guide channels of detachable means for mounting card hangers positioned

therein against movement laterally of the frame, elongated transversely extending card hangers slidably supported by said mounting means and cards carried by said hangers, the said hangers being operatively associated with said mounting means and movable laterally to an offset position with respect thereto and to said frame, each of said card hangers having means for supporting a card for pivotal movement relative to said hangers.

2. In a visible card system, the combination with a frame having guide channels of detachable hanger mounting means positioned therein against movement laterally of the frame, flexible elongated transversely extending hangers

20 slidably supported on and operatively associated with said mounting means, each of said hangers having means for supporting a card for pivotal movement relative to said hangers, said cards and associated hangers being movable laterally to offset positions with respect to said mounting means and said frame.

3. In a visible card system, the combination with a frame having guide channels of a flexible 25 transversely extending card hanger operatively associated with and slidably supported by a detachable mounting means therefor, said hanger having means for supporting a card for pivotal movement relative thereto, said mounting means 30 being positioned within said channels against movement laterally of the frame, and a card swingably carried by said hanger, said hanger and carried card being movable laterally to an offset position with respect to said mounting 35 means and said frame.

4. In a visible card system, the combination with a frame having guide channels of detachable card hanger mounting supports positioned therein against movement laterally of the frame, 40 flexible elongated transversely extending card hangers slidably engaged to said mounting supports and cards carried by said hangers in pivotal relation thereto, said hangers and cards being laterally displaceable with respect to said frame, 45 and means on each of said hangers in operative association with means on a corresponding one of said supports for retaining said hanger in desired position on said frame.

5. In a visible card system, the combination 50 with a frame having guide channels of detachable card hanger mounting supports positioned therein against movement laterally to the frame, flexible elongated transversely extending hangers slidably engaged to said mounting supports, cards 55 engaged to said hangers by swingable mounting means and being normally centrally positioned on said frame and laterally displaceable in either direction from said central position, and means on said hangers in operative association and engageable with means on said supports for retaining said hangers and carried cards in desired 60 position on said supports and frame.

6. In a visible card system, the combination with a frame having guide channels of a flexible 65 elongated transversely extending card hanger operatively associated with and slidably supported by a detachable mounting means therefor, the said mounting means being positioned within said channels against movement laterally of the frame, and a card carried by said hanger in pivotal relation thereto, the said hanger and carried card being movable laterally to an offset position with respect to said mounting means and said frame, and means for retaining said hanger in desired 70 position comprising a surface projection

on said support yieldably engageable with a portion of said hanger.

7. In a visible card system, the combination with a frame having guide channels of a flexible elongated transversely extending card hanger operatively associated with and slidably supported by a detachable mounting means therefor, said mounting means being positioned within said channels against movement laterally of the frame, a card carried by said hanger in pivotal relation thereto, said hanger and carried card being movable laterally to an offset position with respect to said mounting means and said frame, and means for retaining said hanger in desired position comprising lugs projecting from the surface of said support adjacent the ends thereof for yieldable engagement and abutment with end loop portions of said hangers.

8. In a visible card system, the combination with a frame having guide channels of a flexible card hanger operatively associated with and slidably supported by a detachable mounting means therefor, said mounting means being positioned within said channels against movement laterally of the frame, a card swingably carried by said hanger, said hanger and carried card being movable laterally to an offset position with respect to said mounting means and said frame, and means for retaining said hanger in desired position comprising a rib formed on said support for engagement with crimps on said hanger.

9. In a visible card system, the combination with a frame having guide channels of detachable card hanger mounting supports comprising flexible elongated strips positioned therein against movement laterally of the frame, each of said support strips carrying a card hanger slidably engaged therewith and a card swingably engaged to said hanger by swingable mounting means, and means on said support strip for engagement with a hanger portion to retain said hanger and card in desired central or laterally offset position with respect to its support and said frame.

10. In a visible card system, the combination with a frame having guide channels of detachable card hanger mounting supports comprising flexible elongated strips positioned therein against movement laterally of the frame, each of said support strips carrying a flexible card hanger slidably engaged therewith and a card swingably engaged to said hanger, and means on said support strip comprising a rib intermediate the ends thereof for yieldable engagement by positioning crimps formed on the hanger intermediate its end portions to retain said hanger and card in desired central or laterally offset position with respect to its support and said frame.

11. In a visible card system, the combination with a frame having guide channels of detachable hanger mounts comprising flexible elongated strips positioned therein against movement laterally of the frame, each of said strips carrying a flexible card hanger having a card swingably engaged therewith, said hanger and card being shiftable laterally to an offset position with respect to its mount and said frame and operatively associated with said mount, and hanger end loop portions extending within U-bent portions formed adjacent the ends of the mount retaining said hanger in slidable engagement with its mount.

12. In a visible card system, the combination with a frame having guide channels of detachable hanger mounts comprising flexible elongated strips positioned therein against movement later-

ally of the frame, each of said strips carrying a flexible card hanger having a card swingably engaged therewith, said hanger and card being shiftable laterally to an offset position with respect to its mount and said frame and operatively associated with said mount, return bent hanger end portions extending within U-bent portions formed adjacent the ends of the mount retaining said hanger in slidable engagement with its mount, and means for retaining said hanger and card in desired position comprising a rib intermediate the ends of said mount for yieldable engagement by positioning crimps on the hanger.

13. In a visible card system, the combination with a frame having guide channels of detachable hanger mounts comprising flexible elongated strips positioned therein against movement laterally of the frame, each of said strips carrying a flexible card hanger having a card swingably engaged therewith, said hanger and card being shiftable laterally to an offset position with respect to its mount and said frame and operatively associated with said mount, return bent hanger end portions extending within U-bent portions formed adjacent the ends of the mount retaining said hanger in slidable engagement with its mount retaining said hanger in slidable engagement with its mount, and means for retaining said hanger and card in desired position comprising a lug projecting inwardly from the base of each of said U-bent portions for yieldable engagement and abutment with a corresponding return bent hanger portion.

14. An offset mounting device of the class described comprising a flexible hanger mounting strip adapted to be detachably mounted and positioned on a holder frame therefor against movement laterally of the frame, and a flexible elongated metallic card hanger extending longitudinally thereof adapted to support a card in swingable relation thereto, said card being in slidable engagement and operative association with said strip and being movable laterally to an offset position in relation thereto.

15. An offset mounting device of the class described comprising a flexible hanger mounting strip adapted to be detachably mounted and positioned on a holder frame therefor against movement laterally of the frame, and a flexible elongated card hanger, adapted to support a card in pivotal relation to said hanger, said hanger being in slidable engagement and operative association with said strip extending longitudinally thereof and being movable laterally to an offset position in relation thereto, and means for retaining said hanger in desired central or laterally offset position comprising a surface projection on said strip for yieldable engagement with means on said hanger.

16. An offset mounting device of the class described comprising a flexible hanger mounting strip adapted to be detachably mounted and positioned on a holder frame therefor against movement laterally of the frame, and a flexible card hanger, adapted to swingably support a card in pivotal relation to said hanger, said hanger being in slidable engagement and operative association with said strip extending longitudinally thereof and being movable laterally to an offset position in relation thereto, and means for retaining said hanger in desired central or laterally offset position comprising lugs projecting from the surface of said strip adjacent the ends thereof for yieldable engagement and abutment with looped end portions of said hanger.

17. An offset mounting device of the class described comprising a flexible hanger mounting strip adapted to be detachably mounted and positioned on a holder frame therefor against movement laterally of the frame, and a flexible card hanger adapted to swingably support a card in slidable engagement and operative association with said strip and being movable laterally to an offset position in relation thereto, and means for retaining said hanger in desired central or laterally offset position comprising a rib formed on said strip for yieldable engagement with crimps on said hanger.

18. An offset mounting device of the class described comprising a flexible hanger mounting strip adapted to be detachably mounted and positioned on a holder frame therefor against movement laterally of the frame, and a flexible card hanger adapted to swingably support a card in slidable engagement and operative association with said strip and being movable laterally to an offset position in relation thereto, return bent

end portions of said hanger extending within U-bent end portions of said strip retaining said hanger in slidable engagement therewith.

19. An offset mounting device of the class described comprising a flexible hanger mounting strip adapted to be detachably mounted and positioned on a holder frame therefor against movement laterally of the frame, and a flexible card hanger adapted to swingably support a card in slidable engagement and operative association with said strip and being movable laterally to an offset position in relation thereto, return bent end portions of said hanger extending within U-bent end portions of said strip retaining said hanger in slidable engagement therewith, and means for retaining said hanger in desired central or laterally offset position comprising a lug projecting inwardly from the base of each of said U-bent portions for yieldable engagement and abutment with a corresponding return bent hanger end portion.

MARCHAND B. HALL.
